[57] CLAIM

The ornamental design for a chair, as shown and described.

DESCRIPTION

FIG. 1 is a front elevational view of a chair in accordance with the present invention;

FIG. 2 is a back elevational view of the chair of FIG. 1;
FIG. 3 is a right side elevational view of the chair of FIG. 1;

FIG. 4 is a top plan view of the chair of FIG. 1;

FIG. 5 is a bottom plan view of the chair of FIG. 1;
FIG. 6 is a perspective view taken from the left side of the chair of FIG. 1;

FIG. 7 is a front elevational view of a modified form of the chair shown in FIG. 1;

FIG. 8 is a back elevational view of the chair of FIG. 7;
FIG. 9 is a right side elevational view of the chair of FIG. 7;

FIG. 10 is a top plan view of the chair of FIG. 7;

FIG. 11 is a bottom plan view of the chair of FIG. 7; and

FIG. 12 is a perspective view taken from the left side of the chair of FIG. 7.
